CONTROL FOR REFRIGERATION SYSTEMS

Original Filed April 26, 1944

UNITED STATES PATENT OFFICE

2,524,813

CONTROL FOR REFRIGERATION SYSTEMS

Harold F. Lathrop, Philadelphia, Pa., assignor to
General Electric Company, a corporation of
New York

Original application April 26, 1944, Serial No.
532,773. Divided and this application October
21, 1947, Serial No. 781,143

2 Claims. (Cl. 62—8)

1

This invention relates to refrigerating systems and particularly to such systems which are operated at very low temperatures. This application is a division of my copending application Serial No. 532,773, filed April 26, 1944.

In the conventional thermostatic expansion valve there is provided an actuating member responsive to the pressure within the evaporator and which is opposed by an actuating member responsive to the temperature of the refrigerant in the suction line. The pressure responsive member tends to open the valve upon a reduction in pressure and, consequently, when the refrigerating machine is started after an idle period the valve will be opened as soon as the operation of the compressor has reduced the pressure sufficiently to actuate the pressure responsive member. In my copending application Serial No. 532,772, filed April 26, 1944, and which has now matured into Patent No. 2,497,677, granted February 14, 1950, and assigned to the same assignee as the present invention, there is described and claimed a thermostatic expansion valve actuated in response to the difference between the suction line temperature and saturation temperature in the evaporator of the refrigerating system.

When a thermostatic expansion valve is constructed as described in the above mentioned co-pending application Serial No. 532,772, the member responsive to the saturation temperature of the liquid refrigerant tends to close the valve upon a rise in temperature, and should there be no liquid refrigerant in the evaporator when the machine is started, there would be no reduction in temperature sufficient to cool the feeler bulb of the saturation temperature responsive member and open the valve. In my last mentioned co-pending application an arrangement is described for insuring the presence of liquid refrigerant in the vicinity of the saturation temperature responsive control bulb and thereby insuring the opening of the valve when the operation of the system is started. It is an object of my present invention to provide a refrigerating system having an expansion valve controlled by the temperature of the suction gas and the saturation temperature of the liquid refrigerant in the evaporator and provided with an improved arrangement for assuring opening of the valve and operation of the system even though the liquid refrigerant in the evaporator should have been removed prior to starting.

Further objects and advantages of my invention will become apparent as the following description proceeds, and the features of novelty

which characterize my invention will be pointed out with particularity in the claims annexed to and forming a part of this specification.

For a better understanding of this invention reference may be had to the accompanying drawing the single figure of which illustrates diagrammatically a compression type refrigerating system provided with a control embodying my invention.

Referring now to the drawing, the refrigerating system illustrated includes a compressor 1 driven by an electric motor (not shown) and arranged to supply hot compressed refrigerant to a condenser 2. The condenser 2 is cooled by water circulated through a receiver or jacket 3 and the compressed refrigerant is liquefied and flows to a liquid receiver 4. The liquid refrigerant from the receiver 4 is supplied to a multiple conduit evaporator 5 through a liquid line 6 by operation of a solenoid actuated expansion valve 7. The evaporator 5 comprises a plurality of parallel conduits connected to an outlet connection 8 of the valve 7 by a refrigerant distributor 9 which divides the refrigerant equally among the several conduits. The refrigerant in the evaporator absorbs heat from the air to be cooled and is vaporized, and the vaporized refrigerant is returned to the compressor 1 through a suction line 11 manifolded to the several evaporator conduits. The solenoid valve 7 is actuated by a control 12 so that it operates to perform the function of a thermostatic expansion valve and maintain a predetermined amount of superheat in the vaporized refrigerant withdrawn from the evaporator. For this purpose the control 12 is provided with a temperature responsive device 13 including an expandible chamber formed by a bellows 14. The interior of the chamber is in communication through a tube 15 with a feeler bulb or temperature responsive element 16 secured to the suction line 11 so that it is responsive to the temperature of the vaporized refrigerant withdrawn from the evaporator. The control 12 is also provided with an expandible chamber device 17 arranged in opposed relation to the device 13 and comprising a bellows 18 forming an expandible chamber which is in communication through a tube 19 with a temperature feeler bulb 20. The feeler bulb 20 is secured in heat exchange relation with a liquid collecting sump 21 secured in communication with the lowermost conduit of the evaporator indicated at 22. The sump 21, during the normal operation of the evaporator, contains liquid refrigerant, and the device 17 is, therefore, actuated in accordance with the saturation temperature of the liquid refrigerant in the sump 21.

The liquid refrigerant in the sump 21 is at the pressure of the refrigerant in the evaporator so that the temperature of the sump is the saturation temperature of the liquid refrigerant in the evaporator. In some constructions there may be a substantial pressure drop between the inlet end of the evaporator conduits and the suction line 11; and, in such cases, the sump 21 may be located nearer the outlet end of the evaporator conduit so that the pressure in the sump is the same as the suction line pressure and the temperature of the liquid refrigerant in the sump is the saturation temperature of the refrigerant at the pressure in the suction line.

This system is particularly applicable to installations in which a plurality of evaporators are supplied from a single refrigerant condensing unit. The system is arranged to cool a storage chamber or other refrigerated area enclosed by a thermally insulated wall 23, the multiple conduit evaporator 5 being arranged within this chamber. Upon a demand for cooling in the space enclosed by the wall 23, a thermostat 24 closes its contacts and energizes the solenoid valve 7 provided that a switch 25 in the solenoid line has been closed. The actuation of the switch 25 is controlled in accordance with the superheat in the suction line 11 by operation of the opposed actuating members 13 and 17. The switch 25 includes a switch arm 26 which is moved in accordance with changes in the difference of the pressures in the members 13 and 17. The switch arm 26 is pivoted at its lower end to a stationary pivot 27 and the movement produced by the actuating members 13 and 17 is translated into pivotal movement of the arm 26 through coupling members 28 and 29 and a pantograph constructed of links 30, 31, 32 and 33. The links 30 and 33 are pivoted together on the coupling 28; and links 31 and 32 are similarly pivoted on the coupling 29; the lower ends of the links 30 and 31 are pivoted at 27; and the upper ends of the links 32 and 33 are pivoted together and their pivot is slidably mounted in a slot 34 in the arm 26. The couplings 28 and 29 are held apart and in engagement with actuating rods 35 and 36 of the devices 13 and 17, respectively, by a suitable compression spring 37. The movement of the pantograph and resulting pivotal movement of the arm 26 are determined by the difference between the forces of the opposed devices 13 and 17. The switch 25 includes front and back contacts 38 and 39, respectively. The arm 26 under normal operating conditions is biased by a superheat adjusting spring 40 to a position intermediate the contacts 38 and 39 so that the solenoid valve is not energized when the amount of superheat is below a predetermined value. When the superheat rises, a contact 41 on the arm 26 engages the contact 38 and closes the circuit of the solenoid of the valve 7 thereby opening the valve and admitting more refrigerant to the evaporator and lowering the amount of superheat to the predetermined desired value.

Thus under normal conditions of operation the control devices 13 and 17 cooperate to maintain a value of superheat of the vaporized refrigerant in the suction line 11 determined by the setting of the spring 40 by turning of an adjusting screw 42; and during normal operation increased pressure in the element 13 tends to open the valve while increased pressure in the element 17 tends to close the valve. It is apparent, therefore, that on an increase in temperature of the feeler bulb 29 the control device 17 tends to close the valve. If for any reason the temperature of

the bulb 29 is abnormally high and there is no liquid refrigerant in the sump 21 to cool the element 26, it would be impossible to open the valve automatically if some arrangement other than the controls as just described were not provided.

In order to insure opening of the valve upon starting the operation of the refrigerating system, the sump 21 is supplied with heat by an electric heater 43 which is energized on closing of the thermostat 24; the feeler bulb 29 and heater 43, together with the lower portion of the sump 21, are enclosed in an insulated casing 44. It will readily be apparent that should there be no liquid refrigerant in the sump 21 when the thermostat 24 closes its contacts on a call for cooling, the feeler bulb 29 will be heated directly by the heater 43 and the pressure in the device 17 will rise to a high value. The arrangement of the switch arm 26 is such that when this high value of pressure prevails in the device 17, the arm is rotated about the pivot 27 so that a contact 45 engages the back contact 39 and energizes the solenoid of the valve 7 to open the valve thereby admitting liquid refrigerant to the evaporator and placing the system in condition for normal operation to maintain the desired amount of superheat.

The superheat characteristics of the system may further be improved by providing a pressure compensating device 46 directly connected with the suction line through a tube 47 and arranged to bias the switch arm 26 in a clockwise direction so that the bellows 48 tends to keep the switch contacts 38 and 41 out of engagement until a predetermined low pressure has been attained in the evaporator. The superheat setting is then determined by the suction line pressure, which is transmitted to the pressure responsive element 46 in addition to the setting of the adjustable spring 40. This arrangement provides compensation of the superheat setting with pressure changes and results in a more constant value of superheat over a wide range of operating temperatures. It has been found that a valve provided with this additional control may be made to maintain superheat within a range of less than 5° F. over a range of evaporator temperatures from 0° F. to -120° F.

During the operation of the refrigerating system, liquid refrigerant may be available at all times in the liquid line 6 at the solenoid 7; however, the evaporator is supplied with refrigerant only on demand determined by the thermostat 24 which is responsive to the temperature within the space to be cooled. Upon a demand for cooling, the operation of the valve 7 and its associated control mechanism is such that a predetermined value of superheat is maintained in the suction line 11. Should all the liquid refrigerant in the evaporator have been vaporized during a period when there is no demand for cooling, then the excessive pressure created in the control device 17 by the heater 43 upon starting rotates the arm 26 to close contacts 38 and 45. This energizes the solenoid of the valve 7 and insures admission of sufficient liquid refrigerant to the evaporator to enable the control to take up its normal operating functions.

The expandible chamber actuating devices illustrated may be charged with any suitable liquid or gaseous medium which will provide the required operating characteristics. For example, it may be desirable to charge both the suction temperature responsive device and the saturation temperature responsive device with a high pres-

sure gas such as ethane; however, in order to obtain other characteristics it may be desirable to charge one of the devices with one gas and the other with a different gas or one or both of the devices with a vaporizable liquid.

While I have illustrated my invention in connection with the compression type refrigerating systems, other applications will be apparent to those skilled in the art and I do not, therefore, desire my invention to be limited to the particular construction shown and described, and I intend by the appended claims to cover all modifications within the spirit and scope of my invention.

What I claim as new and desire to secure by Letters Patent of the United States is:

1. In a refrigerating system including a condenser and an evaporator and means for withdrawing vaporized refrigerant from said evaporator and returning it to said condenser, an expansion valve for controlling the flow of refrigerant from said condenser to said evaporator, a solenoid for actuating said valve, an electric circuit for said solenoid, control means including a switch in said electric circuit for energizing said solenoid and for actuating said valve to maintain a predetermined amount of superheat in the refrigerant withdrawn from said evaporator, said control means including two opposed expansible chamber devices for actuating said switch, one of said devices being responsive to the temperature of the vaporized refrigerant withdrawn from said evaporator and the other being responsive to the saturation temperature of the liquid refrigerant in said evaporator, both said devices tending to close said switch when the pressure in their respective chambers overcomes the pres-

sure in the chamber of the opposed device, and biasing means for adjusting said devices to determine the amount of superheat maintained by said control means.

2. In a refrigerating system including a condenser and an evaporator and means for withdrawing vaporized refrigerant from said evaporator and returning it to said condenser, a solenoid operated valve for controlling the admission of liquid refrigerant to said evaporator, an electric circuit having a switch therein for energizing said solenoid, temperature responsive control means for actuating said switch, said control means comprising opposed temperature responsive expansible chamber devices arranged to close said switch upon a predetermined change in the differential pressure between said devices, one of said devices having a feeler element arranged to be responsive to the saturation temperature of the liquid refrigerant in said evaporator, and means dependent upon the absence of liquid refrigerant in said evaporator for heating said feeler element to unbalance said control means and open said valve.
